UNITED STATES PATENT OFFICE

JOHN W. REED, OF PHILADELPHIA, PENNSYLVANIA.

RAZOR-BLADE HOLDER.

1,317,316.

Specification of Letters Patent. Patented Sept. 30, 1919.

Application filed November 30, 1918. Serial No. 264,793.

To all whom it may concern:

Be it known that I, JOHN W. REED, a citizen of the United States, residing at Philadelphia, in the county of Philadelphia and State of Pennsylvania, have invented certain new and useful Improvements in Razor-Blade Holders, of which the following is a specification.

One object of my invention is to provide a safety-razor blade holder which will be of simple and durable construction and which can be easily manipulated to strop the blade therein.

Another object is to so construct my improved holder that the blades can be easily and quickly attached thereto and removed therefrom.

A further object is to so construct my invention that it can be easily cleaned and manufactured at a low cost.

These objects, and other advantageous ends which will be described hereinafter, I attain in the following manner, reference being had to the accompanying drawings in which—

Figure 1 is a top plan view of my improved holder having a safety-razor blade secured thereto.

Fig. 2 is a longitudinal section taken on the line 2—2 of Fig. 1.

Fig. 3 is an end view looking in the direction of the right hand end of the holder shown in Figs. 1 and 2, and

Fig. 4 is a longitudinal elevation showing how the main body portion can be made in the form of a die casting in which the blade anchoring pins are made integral in distinction to being made independent, as shown in the construction illustrated in Figs. 1 to 3 inclusive.

Referring to Figs. 1 to 3, inclusive, of the drawing, 5 represents the main body portion or section which throughout the major portion of its length is half-elliptical in cross section and has an upper flat surface 6. A head 7 is formed at one end of the main body portion and projects above the upper flat surface 6 and provides a shoulder 8 which is inclined or beveled in the direction of the extreme end portion 9.

Two pins 10 and 11 are secured within the main body portion 5 and extend upwardly beyond the upper surface 6 and at an incline substantially parallel to the incline of the shoulder 8. These pins 10 and 11 are adapted to project through the holes

12 and 13 in a safety-razor blade 14, such holes being provided in certain well known types of safety-razor blades.

The razor blade 14 is adapted to rest against the upper flat surface 6 and the pins 10 and 11 prevent the movement of the blade in a plane parallel with the plane of the surface 6.

A clamping section 15 has a lower flat surface 16 which is adapted to engage the upper surface of the razor blade and this clamping section has two holes 17 and 18 adapted to receive the upper ends of the pins 10 and 11, said holes 17 and 18 preferably extending at an incline to the lower flat surface 16 so that the pins 10 and 11, holes 12 and 13, and holes 17 and 18 will register with each other, as clearly shown in Fig. 2.

The end 19 of the clamping section 15 is beveled and adapted to abut the shoulder 8 of the main body section 5, when the parts are assembled as shown in Fig. 2. I preferably make the shoulder 8 of greater height than the inclined end 19 of the clamping section 15 and arrange the parts so that under normal condition, as shown in Fig. 2, the top surface 20 of the clamping section is flush with the top surface 21 of the head 7.

By this arrangement, as illustrated, a space 22 is normally provided between the sections 5 and 15. The clamping section 15, throughout the major portion of its length, is also half-elliptic in cross section and follows the contour of the main body section 5.

It will thus be noted that as the assembled holder is grasped by the hand, any squeezing action of the parts of the handle 23 between the razor blade 14 and the shoulder 8 will cause the end 19 of the section 15 to ride downwardly upon the inclined shoulder 8 and thereby impart longitudinal thrust movement to the section 15 relatively to the length of the main body section 5. The pins 10 and 11, being inclined in a direction opposite to the direction of thrust movement, will cause said thrust movement to take the direction of incline of said pins 10 and 11 and thereby securely bind or clamp the razor blade 14 between the surfaces 6 and 16 of the sections 5 and 15 respectively.

To separate the parts of my improved handle, so as to remove the razor blade 14, it is merely necessary to lift the clamping

section 15 from the pins 10 and 11, said lifting action being easily accomplished, if imparted parallel to the incline of the pins 10 and 11 and the shoulder 8. The assembly of the parts is obvious. The razor blade first is slipped over the pins 10 and 11 and the clamping section is then applied so that the pins 10 and 11 project into the holes 17 and 18.

10 A razor blade holder made in accordance with my invention has no projecting screws or other undesirable parts which would interfere with the convenient and comfortable manipulation of the holder to strop the 15 razor blade, and furthermore, both of the parts when detached can be quickly and easily cleaned.

In Fig. 4 I have shown a modification of the main body section which is made in the 20 form of a die casting 24, which has integral pins 25 and 26 which performs the same function as the pins 10 and 11 above described. In all other respects the modification of Fig. 4 is similar in construction and 25 function to that described in connection with the main body section 5, and I have, therefore, given similar parts corresponding reference numerals.

While I have described my invention as 30 taking a particular form, it will be understood that the various parts of my invention may be changed without departing from the spirit thereof, and hence I do not limit myself to the precise construction set forth, but 35 consider that I am at liberty to make such changes and alterations as fairly come within the scope of the appended claims.

Having thus described my invention, what I claim as new and desire to secure 40 by Letters Patent is:

1. A razor blade holder including two sections, one of said sections having a pin adapted to extend through a hole in a razor blade placed between said sections and extending at an incline to the plane of said blade, the other of said sections having a hole adapted to receive the portion of said pin projecting through said blade, said sections having extended portions providing a 45 handle, said portions having engaging parts thereon adapted, when the handle portions are squeezed together, to impart a relative longitudinal movement between said sec-

tions whereby the sections are moved together at their portions between which the 55 blade is positioned due to the incline of said pin so that the blade is securely held between said sections; substantially as described.

2. A razor blade holder including two 60 sections; said sections having surfaces adapted to engage the opposite faces of the razor blade, one of said sections having a pin adapted to extend through a hole in said razor blade at an incline to the plane 65 of said blade, the other of said sections having a hole adapted to receive the portion of said pin projecting through said blade; one of said sections having an inclined shoulder, the other of said sections having a portion adapted to engage said inclined shoulder and thereby impart thrust movement to one of said sections relatively to the other; said inclined pins being operative to convert said thrust movement into 70 a movement which causes said sections to clamp the razor blade between them; substantially as described.

3. A razor blade holder including two sections; said sections having surfaces 80 adapted to engage the opposite faces of the razor blade, one of said sections having a pin adapted to extend through a hole in said razor blade at an incline to the plane of 85 said blade, the other of said sections having a hole adapted to receive the portion of said pin projecting through said blade; one of said sections having a head thereon providing an inclined shoulder, the other of said sections having a portion adapted to 90 slidably abut said shoulder whereby a squeezing movement of said sections toward each other will impart a relative thrust movement between said sections; said inclined pin serving to convert said thrust 95 movement in a direction to clamp the blade between said sections; substantially as described.

In testimony whereof I have signed my name to this specification in the presence of 100 two subscribing witnesses.

JOHN W. REED.
